UNITED STATES PATENT OFFICE.

WILLIAM T. LOVE, OF LOMAX, ILLINOIS, ASSIGNOR TO E. M. LOVE, OF LOMAX, ILLINOIS.

OIL-CAN.

1,113,453.

Specification of Letters Patent.

Patented Oct. 13, 1914.

Application filed November 15, 1913. Serial No. 801,290.

To all whom it may concern:

Be it known that I, WILLIAM T. LOVE, a citizen of the United States, residing at Lomax, in the county of Henderson and State 5 of Illinois, have invented certain new and useful Improvements in Oil-Cans, of which the following is a specification.

My invention relates to cans, and more particularly to that class of such containers 10 adapted to be provided with means adapted to facilitate the filling of other vessels therefrom.

The object of this invention is to provide 15 an oil container of the character described which shall have embodied therein means for effectually preventing the overflow of a vessel which is being filled by the oil poured from the container.

A further object of this invention is to 20 provide an oil can embodying an improved construction by means of which the above result is secured.

With these and other objects in view my 25 invention consists in the peculiar combination and arrangement of the various parts of a safety oil container as herein described, and more particularly set forth in the appended claims.

Referring to the drawings wherein similar 30 reference numerals indicate similar parts wherever used, Figure 1 is a side elevation of my device; Fig. 2 a vertical section through the same; Fig. 3 a transverse section taken on line 3, 3 of Fig. 2, and Fig. 35 4 a detail section showing the operation of the device.

The numeral 5 designates a can preferably cylindrical, provided with the usual bail 6, pouring spout 7 and handle 8 for aid 40 in tipping the device. In the top of the can is formed the usual filling opening 9 provided with a knurled screw cap 10. Leading from the filling opening 9 and extending downwardly into the body of the can 45 is a short pipe 11, provided with an elbow 12 which has attached thereto a longer pipe 13 extending at right angles to the pipe 11, the pipe 13 extends outwardly into a chamber 14 formed in the body of the can and 50 covered by cap 15. The pipe 13 is open at its end 16, which extends within the chamber 14, so that when the can is being filled the oil or other liquid being placed therein will run through the pipes 11, 12, 13 and out

through the opening 16 into the chamber 55 14, and thence into the body of the can.

The spout 7 is provided in its interior with a small air tube 17 which extends outwardly to the mouth 18 of the spout and downwardly to an elbow 19 within the can 60 body, where it is provided with an extension 20 extending across the interior of the can body and open at its end 21. This tube serves the purpose of cutting off the flow of oil from the can into another vessel being 65 filled from the can when the level of the oil in the vessel being filled reaches the spout, thus cutting off the flow of air through the tube at the point 18. Heretofore devices of this character have been more or less faulty, 70 in that should the cap 9 become in any way punctured or the threads thereof become jammed so that air would leak around the cap 9, thus giving access to the interior of the can the flow of oil would not be stopped, 75 and thus the vessel being filled would consequently overflow.

With the present device when the can is tipped sufficiently to pour oil out of the spout 7, as shown in Fig. 4, the oil fills 80 the chamber 14, thus effectually sealing the open end 16 of the tube 13, so that should there be any leak around the cap 9 of the tube 10 there would not be any air admitted 85 to the interior of the can, as the oil or liquid contained within the chamber 14 would prevent the same from entering the interior of the can. By this it will be seen that the can would be effectually sealed and that the instant the level of the oil covered the tip 90 18 of the pipe 17 all further pouring of oil from the can would at once be stopped, and the danger of overflow from the vessel being filled from the can would thus be prevented.

Considerable variation of the details of this invention may be resorted to without departing from the spirit thereof, and it is not my intention to confine myself to the specific form shown herein, but to construe 100 the appended claims as broadly as permissible in view of the prior art.

Having thus described my invention what I claim as new and desire to secure by Letters Patent is:

1. The combination with a receptacle having a filling aperture and a pouring spout, of an air tube in said pouring spout extend-

95

105

- ing into said receptacle, a pipe connecting with said filling aperture and extending into said receptacle and opening into a chamber formed in the wall thereof on the pouring side of the can, whereby when the receptacle is tilted to pour therefrom the liquid will fill said chamber and close said filling pipe, and the level of liquid in the vessel being filled will close the pouring spout and prevent any further flow of liquid therefrom.
2. The combination with a receptacle having a filling aperture and a pouring spout, said receptacle being provided with a chamber formed in the wall thereof on the pouring side of the can, of an air tube in said

pouring spout extending into the receptacle, a pipe connected with said filling aperture and extending downwardly and forwardly into said receptacle and opening into the chamber formed in the wall thereof, whereby when the receptacle is tilted to pour therefrom the liquid will fill said chamber to close said filling pipe to exclude all air entering therefrom. 20

In testimony whereof I affix my signature 25 in presence of two witnesses.

WILLIAM T. LOVE.
